(57) **CLAIM**

The ornamental design for a beverage dispensing bar gun, as shown and described.

DESCRIPTION

FIG. 1 is a top plan view of a beverage dispensing bar gun showing my new design;

FIG. 2 is a left side elevational view thereof;

FIG. 3 is a bottom plan view thereof;

FIG. 4 is a right side elevational view thereof;

FIG. 5 is a front elevational view thereof;

FIG. 6 is a rear elevational view thereof;

FIG. 7 is a perspective view thereof;

FIG. 8 is a cross-sectional view thereof taken along line 8-8 in FIG. 2; and,

FIG. 9 is a cross-sectional view thereof taken along line 9-9 in FIG. 2.

The drawings are lined for contrast in appearance. The broken lines depict portions of the beverage dispensing bar gun that form no part of the claimed design.

1 Claim, 5 Drawing Sheets
